Isaac A. Prinelle

United States Patent Office.

GEORGE WILKINSON, OF PROVIDENCE, RHODE ISLAND, ASSIGNOR TO THE GORHAM MANUFACTURING COMPANY, OF SAME PLACE.

Design No. 2,993, dated April 7, 1868.

DESIGN FOR A FORK OR SPOON-HANDLE CALLED "IONIC."

The Schedule referred to in these Letters Patent and making part of the same.

TO ALL WHOM IT MAY CONCERN:

Be it known that I, GEORGE WILKINSON, of the city and county of Providence, and State of Rhode Island, have originated a new Design for Articles of Silver, and other metals and plated ware, of which the following is a full, clear, and exact description, reference being had to the accompanying specimens or drawings, making part of this specification; that is to say, for a design called the "Ionic," for the handles of spoons, forks, and other table-ware and implements, of which—

Figure 1 is a view of the front side of the said design, and

Figure 2 is a view of the back side of the same—

Similar letters indicating like parts in both figures.

The said design consists of the general outline, shape, form, or contour of the handle, as represented, with ornamental configurations or embellishments of a character suited thereto.

The said outline comprises a flat tapering stem or shaft, I, an oval shape, S, and a pointed paddle-blade shape, A.

The ornamentation is that represented in the drawings, consisting of a double-beaded edge terminating in a point, and enclosing a figure, e, near the bowl F, and a rosette upon the oval, S, with ornament of Grecian honeysuckle extending each way therefrom, upon the blade A and shaft I, for the front side; and upon the back side, fig. 2, a single bead, conforming to the outline, within the edge thereof, terminating with a sprig of honeysuckle, d, and with a simple figure, composed in part of sprigs of honeysuckle, upon the oval shape S.

Claim.

I claim the design for the handles of spoons, forks, &c., of the general outline or contour, and with ornamental configurations, as herein set forth and shown.

GEO. WILKINSON.
